ORNAMENTATION FORMING AND FEEDING APPARATUS

Walter A. Herrmann and Christ Adensam, Chicago, Ill., assignors to L. G. Blessing

Application May 13, 1939, Serial No. 273,532

13 Claims. (Cl. 28—2)

This invention relates to ornamentation forming and feeding apparatus, and more particularly to an apparatus for automatically applying tufts, tassels, and the like to the loops of looped headings used on drapes, curtains, and similar articles.

One feature of this invention is to provide automatic means for forming ornamentation in which the loops of a looped heading encircle tufts, tassels, and the like; another feature of this invention is to automatically feed the looped heading into a machine applying the ornamentation; still another feature is the automatic removal of the loops from the ornamentation forming machine; other features and advantages will be apparent from the following specification and drawings, in which:

Fig. 1 is an end elevational view, partly broken away and partly in section, of an embodiment of my invention; Fig. 2 is a view taken along the line 2 of Fig. 1, showing particularly the feed mechanism for the looped heading; Fig. 3 is a detail plan view of the roller arrangement used for the feed mechanism; Fig. 4 is a sectional view taken along the line 4 of Fig. 3; Fig. 5 is a fragmentary sectional view taken along the line 5 of Fig. 1; Fig. 6 is a fragmentary detail view of the loop heading guide rod and loop receiving collar in open position; Fig. 7 is a similar view of the same parts in overlapping position; Fig. 8 is a fragmentary sectional view along the line 8 of Fig. 7; Fig. 9 is a detail plan view of the collar and loop guide rod, showing a loop in position on the collar; Fig. 10 is a detail plan view of the same members in overlapping position; Fig. 11 is a view along the line 11 of Fig. 9, showing the mechanism for releasing the loop from the collar; Fig. 12 is a detail view of the same parts, showing the loop releasing mechanism in vertically advanced position; Fig. 13 is a similar detail view, showing the loop releasing mechanism at the completion of its cycle of movement; Fig. 14 is a fragmentary sectional view of the collar with a tassel therein in position for binding; Fig. 15 is a similar view of the same parts after the tassel is bound.

This invention is described herein in connection with a tassel forming machine, a device which is well known in the art. Such a machine is shown and fully described in Walliser Patent No. 1,663,534.

The device described in Walliser Patent No. 1,663,534 is designed for forming tassels on fringe and loop heading material, and the like. In this device the heading material is maintained in a

fixed position while threads forming a warp are passed through the loop thereof. The warp is then cut and bound in the form of a tassel. In order to operate the Walliser device, it is necessary, however, to manually feed and remove the heading material from the machine. In our invention, we have obviated this and other difficulties by providing simple automatic means for feeding the heading material into the tasseling machine and removing the finished product therefrom.

Broadly, our improved mechanism operates to feed loops or extension threads of a heading material to the tassel forming collar of the said Walliser Patent No. 1,663,534, whereby in the well known operation of the tassel forming machine described therein, a tassel is secured to the loop as it is extended around said collar. Thereafter, by means of our mechanism, the heading material, loop, and the attached tassel are removed from the machine.

Our improved mechanism may also be used with other types of ornamentation applying machines such as the machine shown and described in the patent to C. F. Arnold, No. 1,390,267. In connection with the Arnold machine, our mechanism may be used to feed a looped heading to the forked die in which the tuft is formed and bound.

In the construction of this invention as illustrated in the drawings and as seen particularly in Fig. 2, A designates the tassel forming part of the Walliser machine; B designates our improved feed mechanism; and C the mechanism for the removal of the heading after the forming of the tassel.

The tassel forming part of the machine is shown and fully described in Walliser Patent No. 1,663,534 and need not, therefore, be described here in detail. It is believed to be sufficient to mention the main operating features and their cooperation with the other parts of our machine.

As shown particularly in Fig. 1, the main drive shaft 20 driven by a motor or other suitable power means (not shown) in turn drives the bevel gear 21 on the shaft 22. At the opposite end of the shaft 22 is mounted a gear 23 meshing with the gear 24 on the shaft 25. The upper end of this shaft 25 carries the cam 26.

An arm 27, pivotally mounted on the bracket 28, carries a roller 29 engaging the periphery of said cam 26. The roller is urged into yielding engagement with the cam by a spring 30 attached to the extension 31 on the arm 27. At the other end of the arm 27 is mounted an interrupted circular member 32, or collar, adapted to

10

receive warp threads or other ornamentation therein. The nature of this device and its function is fully described in Walliser Patent No. 1,663,534. As therein stated, this collar is provided with a shoulder 32^a which may be encircled by a loop 33 of a looped heading 34. A strand of warp 35 may then be inserted in the collar and loop. The warp is severed above and below the collar. The projecting ends of the warp are then drawn together and bound by a wire 36 in the form of a tassel, as seen in Figs. 14 and 15. The mechanism for forming the warp into a tassel forms no part of the present invention, being well known in the art and described in said patent.

The present invention is chiefly concerned with the mechanism for feeding and removing the looped heading and with the actuation of the arm 21 and collar 32 in cooperation with the tassel forming machine.

Referring to Fig. 5, the feed mechanism B is actuated by the shaft 20. Two projecting cams 37 and 38 are mounted on this shaft. The frame 39^a carries a pivot 40, on which is mounted the member 41. The lower portion of the member 41 carries a round and horizontally projecting lug 42 adapted to engage the bevelled surface of the cam 37 rotating upon the shaft 20. An arm 43 is pivotally mounted on the upper portion of the member 41 and is secured in place by a pin 44. A coil spring 45, also mounted on the member 41, urges the rod 43 downwardly. A spring 46, secured to the lower end of the member 41, urges the member towards the position shown in Fig. 5.

A member 47 is pivotally mounted on the arm 48 carried by the frame 39^a. The lower end of this member is formed in the shape of a small cylinder 49, the side of which is adapted to be engaged by the bevelled surface of the cam 38. A spring 50, secured at one end to the member 47 and at the other to a pin 51 on the frame 39, urges the member to the position shown in Fig. 5.

An extension 52 of the frame 39^a carries a pair of bars 53 and 54 pivotally mounted in scissor-like arrangement on said extension. As shown particularly in Figs. 3 and 4, adjacent ends of the bars carry depending rollers 55 and 56. The opposite ends of the bars support pins 57 and 58, the pins being provided at the upper ends thereof with annular bevelled grooves 59 and 60 adapted to carry a magazine rod or loop supporting member 61. The ends of the bars upon which the pins 57 and 58 are mounted are normally held in adjacent relation by the spring 62.

The member 41 is equipped at its upper end with a projecting wedge portion 63, which is adapted to be received between rollers 55 and 56. The magazine rod or loop supporting member 61 is mounted at one end in any suitable means, preferably a fixed means, from which it may readily be removed for loading, such as the clamp 64. The rod or member 61 is thus supported with a free end 96 adjacent the collar 32 when the latter is moved from the tassel-forming position. Said free end is cut away at 67 to provide a recess 97 adapted to overlap the collar 32, as shown in Figs. 7 and 8. Intermediate of its ends the rod 61 is, as previously stated, carried in the grooves 59 and 60. As seen particularly in Fig. 8, the upper surface of the rod 61 is provided with a series of longitudinal grooves 65 adapted to receive fingers or prongs 66 of the arm 43.

The operation of the feed mechanism is as follows. By opening the clamp 64, the magazine rod or loop supporting member 61 may be removed from the machine. Heading material is then secured to the rod by placing the loops thereon. The rod 61 is then replaced in the machine and secured in position by the clamp 64 and the grooves 59 and 60.

The rotation of the shaft 20 serves to move the arm 21 and the tassel forming collar 32 thereon in cooperation with the feed mechanism B. The bevel gear 21, the shaft 22, and the gear 23, all driven by the shaft 20, in turn drive the gear 24, the shaft 25, and the cam 26. The roller 29, engaging the cam 26, causes the arm 21 to reciprocate horizontally about the pivot 28. The collar 32 is thus moved from tassel forming position, as shown in Fig. 2 and Fig. 9, to a position adjacent the guide rod 61, as shown in Fig. 10, and upon receiving one of the loops 33 is returned to its original position.

The operation of the feed mechanism B in cooperation with the movement of the collar 32 is clearly shown in Fig. 5. The operation of the drive shaft 20 causes the cams 37 and 38 to rotate thereabout. The cam 37 strikes the roller 42, moving the member 41 to the position shown in dotted lines. In this movement the arm 43 travels along the upper surface of the magazine rod or loop supporting member 61, drawing the loop 68 over the end of this rod. The prongs 66, moving in the grooves 60, prevent the arm 43 from slipping over the loop 68. As the cam 37 is moving the member 41, the cam 38, by engaging the cylindrical extension 49 of the member 47, moves this member to the position shown in dotted outline. When the member 47 is moved, the wedge 63 is inserted between the rollers 55 and 56, spreading the pins 57 and 58 against the spring 62. This permits the rod 61 to fall to the lower position between the grooves 59 and 60, as shown in Fig. 4.

As shown particularly in Figs. 6, 7 and 8, when the rod 61 falls to lower position, the cutaway portion 67 of the free end 96 is brought into juxtaposed relation with the collar 32 which, in the meantime, has been moved to position adjacent the end of the rod or loop supporting member 61. In this position the recessed portion 97 of the rod 61 overlaps or telescopes the top of the collar 32. As a result, when the loop 68 is drawn over the end of the rod 61, it must encircle the collar 32.

When the cams 37 and 38 pass the roller 42 and cylinder 49, respectively, the members 41 and 47 return to their original positions. The wedge 63 is withdrawn from the rollers 55 and 56. The grooves 59 and 60 are, therefore, brought together, raising the rod 61 to the position shown in Fig. 5. The rearward movement of the upper end of the member 41 carries the arm 43 rearwardly along the upper surface of the rod 61. The prongs 66 raise from the grooves 60 as they pass over the loop 68, dropping back into the grooves immediately thereafter. The collar 32, after receiving a loop, is carried by the arm 21 to the position shown in Figs. 9 and 2, where it receives the warp 35, and a tassel is formed.

The tassel removing mechanism C, shown particularly in Fig. 1, may be actuated by the vertically bevelled cam 69 carried by the shaft 25. The frame 39 supports a bracket 71, which furnishes a pivotal mounting at 95 for the member 72, which, in turn, is provided with an elongated 75

cylindrical extension 73 adapted to engage said cam. A spring 72^a, secured to the member 72, urges the extension 73 upwardly into such engagement. A flat plate 74 is pivotally secured to the other end of the member 72 by the pivot 75. The plate 74 carries on its upper end a removing arm 76 attached to the plate by rivets 77. A link 78 is attached at one end by a rivet 79 to the plate 74 intermediate of the ends thereof, 10 and at the other end by a rivet 80 to a depending extension 81 of the pull rod 82. The pull rod 82 is slidably mounted in the casing 83 carried by the frame 39. As shown in Fig. 2, the pull rod 82 is provided at one end with a lateral projection 15 84 attached to the spring 85, which is secured at its other end to the casing 83. On the other end of the pull rod 82 is mounted a roller 86 adapted to engage the cam 87. The cam 87 is mounted on the shaft 88 driven by the bevel gears 89 and 90. The bevel gear 90 in turn is driven by the shaft 91, the bevel gear 92, and the shaft 23.

The removing arm 76, as shown in Figs. 9 to 13, is equipped at its end with a lateral extension 93 and a vertical projection 94. The lateral extension 93 is adapted to receive that portion of the loop 33 which connects the collar 32 with the heading material 34. When the arm 76 is raised, the extension 93 is thus enabled to lift the loop 33 from the shoulder 32^a of the collar 32, as shown in Fig. 12. Thereafter, upon lateral movement of the arm 76, the projection 94 removes the loop 33 and tassel from the collar 32, as shown in Fig. 13.

The operation of the removing mechanism C 35 is as follows:

The rotation of the shaft 25, driven by the gears 23 and 24, the shaft 22, the gear 21, and the main drive shaft 20, causes the cam 69 to rotate. When the cam 69 engages the cylindrical extension 73, the member 72 moves vertically about the pivot 95, lifting the plate 74 and the arm 76.

The cam 87, driven by the shaft 88, gears 89 and 90, the shaft 91, gear 92, and the main drive shaft 20, is arranged to cooperate in operation with the cam 69. The cam 87 permits the roller 86 and pull rod 82 to be moved laterally by the spring 85 when the recess 98 is engaged by the roller 86. The lateral movement of the pull rod 50 82 is then communicated to the plate 74 and arm 76 by the link 78. Thus by proper arrangement of the cam 87 and cam 69, the arm 76 is moved, first vertically, and then laterally.

As shown in Figs. 9 to 13, the successive vertical and lateral movements of the arm 76 serve to lift the loop 33 from the shoulder 32^a of the collar 32 and then further separate the loop and heading material from the collar 32 by lateral movement. By using the spring 85 rather than rigid 60 means to cause lateral movement of the arm 76, danger of tearing the ornamentation in the event the loop 33 should become caught on the collar 32, is obviated.

The rotation of the cams 69 and 87 is so arranged that when the loop 33 has been removed from the collar 32 the extension 73 is disengaged and the roller 86 is forced from the recess 98. The arm 76 is then returned to its original vertical position by the spring 72^a. At the same 70 time the pull rod 82 and link 78 cooperate to move the arm 76 laterally to the original position shown in Fig. 11.

To summarize the operation of the machine, loops loaded on the rod or loop supporting member 61 are successively fed to the collar 32 by the

member 43. As each loop is received by the collar 32, the collar is returned to tassel-forming position and a tassel formed thereon in the manner described in said Wallister patent. The loop is then removed from the machine by the means just described, and the collar 32 is returned to a position adjacent the rod 61 to receive another loop.

While in the foregoing description we have set forth certain specific structures as illustrating our invention and described the same in connection with specific ornamentation applying machines, it will be obvious that many modifications may readily be made by one skilled in the art without departing from the spirit of our invention. For instance, in addition to feeding loops to a collar member, the mechanism may be used for placing loops about or removing therefrom other parts of machines wherein different types of ornamentation may be fixed thereto. It will 15 also be apparent that our improved mechanism may be used with any device wherein the automatic feeding or removal of loops is desired.

While we have illustrated and described a particular construction embodying our invention, we 25 do not wish to be understood as intending to limit it thereto, as the same may be variously modified and altered without departing from the spirit of our invention.

We claim:

1. In combination with an ornamentation forming machine equipped with a part adapted to receive warp threads, a loop supporting member, means for bringing said member and said part into juxtaposed relation, and non-loop-supporting means for drawing a loop from said member to encircling position about said part.

2. In a combination with an ornamentation forming machine equipped with a slotted part adapted to receive warp threads, feed mechanism 40 for placing loops successively upon said part comprising, a rod member carrying thereon loops connected to a heading, means for bringing said part and said member into cooperative relation wherein said loops may be transferred to said part, and non-loop-supporting means for drawing a loop at the forward end of said rod onto said part to encircle the part and the slot therein.

3. In combination with an ornamentation forming machine equipped with a collar for receiving ornamentation therein, a loop-holding rod provided at one end with a cutaway portion adapted to overlap said collar, means for bringing said collar and said rod into juxtaposed relation wherein said end of said rod overlaps said collar, and non-loop-supporting means for drawing a loop from the overlapping end of said rod to said collar.

4. In combination with an ornamentation forming machine equipped with a collar for receiving ornamentation therein, said collar being provided with a shoulder portion adapted to receive a loop thereabout, a rod adapted to carry the loops of heading material, said rod being provided at one end with a recess for receiving said collar, means for bringing said collar and said rod into juxtaposed relation wherein a portion of said collar is received within said recess, and means for drawing a loop of the loop heading from said end of the rod to the shoulder portion of said collar.

5. In combination with an ornamentation forming machine equipped with a part for receiving ornamentation, a loop-holding rod, means for bringing the forward end of said rod into a position over said member and for separating said

5

30

35

40

45

50

55

60

65

70

75

rod and member, and non-loop-supporting means for drawing a loop from the forward end of said rod to said member while the said rod is in a position over said member.

5. 6. In combination with a tassel forming machine equipped with a collar adapted to be moved into and out of tassel-forming position, a feed mechanism for placing loops of a heading material successively upon said collar comprising, a 10 loop-holding rod supported with a free end adjacent said collar when said collar is in non-tassel forming position, and non-loop-supporting means for drawing a loop from the free end of said rod onto said collar when said collar is moved 15 to a position adjacent the end of said rod.
7. In combination with an ornamentation forming machine equipped with a slotted collar for receiving ornamentation therein, said collar being provided with a shoulder for receiving a 20 loop thereabout and being adapted to be moved into and out of ornamentation forming position, a loop-holding rod supported with a free end adjacent said collar when out of ornamentation forming position, means for bringing said collar to a position adjacent the free end of said rod, and for returning said collar to ornamentation forming position, means for drawing a loop from the free end of said rod to the shoulder of said 25 collar when in said position adjacent the free end of said rod, and means for forming ornamentation within said loop when the collar is in said ornamentation-forming position.

8. Apparatus of the character described for forming ornamentation on a heading material 30 comprising, a movable collar member adapted to receive said ornamentation, a rod for carrying loops connected to said heading material, said rod being provided at one end with a cutaway portion adapted to overlap said collar, means for 35 bringing said collar from ornamentation forming position to a position adjacent the end of said rod, and for returning the collar to ornamentation forming position, means for bringing the end of said rod into overlapping relation with said collar, and non-loop-supporting means for drawing 40 a loop from the end of said rod onto the collar when overlapped by the end of said rod.

9. In combination with an ornamentation forming machine equipped with a collar for receiving ornamentation therein, a loop-holding rod supported with a free end adjacent said collar, said rod being provided at said end with a recessed portion adapted to receive said collar, means for bringing the free end of said rod into overlapping 45

relation with said collar, and non-loop-supporting means for drawing a loop from the free end of said rod onto said collar.

10. In combination with an ornamentation forming machine equipped with a slotted part 5 adapted to receive warp threads, feed mechanism for placing loops successively upon said part comprising, a rod member carrying thereon loops connected to a heading, said rod member being provided with at least one longitudinal groove 10 therein, means for bringing said part and said member into cooperative adjacent relation wherein loops may be transferred to said part, and means for drawing a loop from the forward end of said rod onto said part to encircle the part and the 15 slot therein, said last mentioned means including an arm having a finger engaging said longitudinal groove.

11. In an ornamentation forming machine 20 equipped with a collar for receiving ornamentation therein, a feed mechanism for placing loops successively upon said collar comprising a loop supporting rod member provided at one end with a cutaway recessed portion adapted to overlap said collar, said rod member having a plurality 25 of longitudinal grooves on the surface thereof, means for bringing said end of said rod member into overlapping relation with said collar, and means for drawing a loop from said end of said rod member onto said collar, said means including an arm angularly disposed to said rod member and provided with a plurality of fingers 30 adapted to engage the longitudinal grooves therein.

12. In ornamentation forming apparatus of the 35 character described equipped with a part adapted to receive warp threads, a loop supporting member, means for bringing said member and said part into juxtaposed relation and for separating said member and part, and non-loop-supporting 40 means for drawing a loop from the end of said loop supporting member on to a portion of said part when said part and loop supporting member are in juxtaposed relation.

13. In ornamentation-forming apparatus of the 45 character described equipped with a part adapted to receive warp threads, a loop-supporting member, non-loop-supporting means for drawing a loop from the end of said loop-supporting member into a position for engagement with a portion 50 of said part, and means for moving said part into engaging relation with said loop.

WALTER A. HERRMANN.
CHRIST ADENSAM.
